UNITED STATES PATENT OFFICE.

LOUIE T. LA PAUGH, OF UTICA, NEW YORK.

OUTLET-BOX.

No. 854,045.

Specification of Letters Patent.

Patented May 21, 1907.

Application filed February 7, 1906. Serial No. 289,954.

To all whom it may concern:

Be it known that I, LOUIE T. LA PAUGH, a citizen of the United States, residing at Utica, in the county of Oneida and State of New York, have invented certain new and useful Improvements in Outlet-Boxes; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in outlet boxes for electric conduits, and consists in the provision of a novel manner of fastening the cover to the box, involving a saving of labor and material and providing a secure and inexpensive fastening means, doing away with inwardly or outwardly bent ears which are commonly formed upon junction boxes and which are frequently liable to break off.

In order to make steel drawn boxes with ears bent at right angles to the wall of the box, a very ductile and high grade steel must be used, and in so doing, the operation of blanking and drawing a box without heating or reheating, hardens the steel to such a degree that it is very difficult to bend the parts of the box at right angles to the sides without breakage, for the reason that the operation of drawing a box out of one piece of steel will necessarily destroy or weaken the fiber of the metal, thereby weakening the ears at the point of bending, and it is the aim of the present invention to produce a box without any inwardly or outwardly extending lugs, to obviate these objections.

The invention consists further in various details of construction and arrangements of parts which will be hereinafter fully described and then specifically defined in the appended claims.

I illustrate my invention in the accompanying drawings, in which:

Figure 1 is a perspective view showing an outlet box with the cover secured thereto and made in accordance with my invention. Fig. 2 is a perspective view showing the cover and box disassembled. Fig. 3 is a sectional view, vertically and centrally through the box on line 3—3 of Fig. 1. Fig. 4 is a perspective view of my invention as applied to a square box and cover. Fig. 5 is a per-

spective view of the form of box shown in Fig. 4, the cover and box being disassembled. Fig. 6 is a perspective view of an outlet box showing a slight modification in the detailed construction of the cover in which a lip upon the cover is adapted to hook into a slot in the wall of the box, the cover and the box being shown as disassembled. Fig. 7 is a perspective view with the parts disassembled, showing a square box, of the modification illustrated in Fig. 6. Fig. 8 is a perspective view showing a modified form of fastening means. Fig. 9 is a sectional view on line 9—9 of Fig. 8, and Fig. 10 is a detail perspective view of a portion of the box with a fastening lug detached therefrom.

Reference now being had to the details of the drawings by letter, A designates a box of circular outline with a turned-down angular lip B formed integral with the cover B'. Said box A has an elongated slot A' formed preferably adjacent to the upper open edge of the box and is provided to receive said angled lip B in the manner shown clearly in Fig. 3 of the drawings. At suitable locations about the flange of said cover are downwardly bent lugs C which, in Figs. 1 to 3 of the drawings, are shown as engaging the surface of the side wall of the box and serve to hold the cover from lateral movement. At a position diametrically opposite the slot A' is formed a second slot D adapted to receive a fastening member E which has shoulders E' formed at the upper end of the flaring portions of said member, and the portion of said member above said shoulders is bent at right angles and projects through said slot D, and has a threaded aperture F therein adapted to receive a screw F'. Said cover has a slotted extension H designed to receive the body portion of the screw F', the head of the screw being adapted to bear against the upper surface of the projecting or extending portion of the cover when the screw is turned down.

Referring to Figs. 4 and 5 of the drawings, will be seen the application of my invention to a square box and in which figures, I have illustrated a plurality of angled lips B which are formed integral with the cover and are adapted to engage slots A' formed in the side wall of the box adjacent to the upper marginal edge thereof. Said cover illustrated in Fig. 4, it will be noted is provided with the angled lugs C which engage the outer surface of the box and serve to hold the cover from lateral movement, and the fastening

means comprising the separate detachable member E is similar in construction to the one illustrated in Figs. 1 to 3 of the drawings, and as hereinbefore described.

5 In Figs. 6, 7 and 9 of the drawings, I have shown a slight modification in the manner of construction of the cover of the box in which I illustrate the lip J which is formed integral with the cover B', in the shape of a hook adapted to be inserted through the slot A', from the outside, forming a hinge connection, and the angled lugs C' which are formed about the marginal edge of the flange of the cover are adapted to engage the outer surface of the 15 wall of the box instead of the inner surface, as illustrated in Figs. 1 to 5, inclusive, the purpose, however, of the lugs being to prevent a lateral movement of the cover, as in the other figures of the drawings.

20 In Fig. 7 of the drawings, I have shown the application of the modification illustrated in Fig. 6 to a square box and cover corresponding, and in said Fig. 7 is illustrated a plurality of the hooked lips J which engage a plurality of slots A'.

25 In Fig. 8 of the drawings, I have shown a slightly different form of fastening means in which the clip K is provided with a threaded aperture to receive the screw F while the inner 30 end of said clip, a detail of which is shown in Fig. 10, is split and adapted to be bent in the form illustrated in order to securely hold said clip in place.

35 In applying the cover to an outlet box made in accordance with my invention, it will be noted that it will not be necessary to remove the screw from the member E carried by the box after said screw has once been inserted in the threaded aperture therein at the 40 factory, it only being necessary to loosen the screw slightly, which will allow the angled member E to tilt sufficiently to cause the screw to engage the slotted extension of the cover, after which a slight lateral play toward the screw may be imparted to the cover to allow the angled lips or the hook modification illustrated in Figs. 6 and 7, to be inserted in a slot or slots A' in the wall of the 45 outlet box, after which the screw may be 50 tightened, which will cause the downwardly extending portion of said member E to form a lever against the screw and by reason of the shoulders, said member will be securely held

within the box, and as the screw is tightened, drawing the slotted extension against the 55 upper edge of the box, the parts will be securely held together, the angled lugs C preventing any lateral movement of said cover.

60 In the modification shown in Figs. 6 and 7 of the drawings, the lips, which are of hook form, are inserted from the outside through the slots A', and the cover otherwise fastened in a similar manner as described.

65 From the foregoing, it will be noted that by the provision of an outlet box made in accordance with my invention, all integral lugs which are struck up from the sides of the box are dispensed with, thus forming a more substantial and economical box in which the cover may be easily and quickly applied to 70 or removed therefrom.

75 What I claim is:

1. An outlet box having a slot in the wall thereof, a cover having an integral lip adapted to engage said slot, a loosely mounted member having an angled part projecting through an aperture in the wall of the box, and fastening means engaging said member and cover to hold the latter in place, as set forth.

80 2. An outlet box having a slot in the wall thereof, a cover having an integral lip adapted to engage said slot, a loosely mounted member having an angled portion passing through an aperture in the wall of the box, and fastening means engaging said member and cover whereby the latter may be held to the box, and means for holding said member within the box, as set forth.

85 3. An outlet box having a slot in the wall thereof, a cover having an integral lip adapted to engage said slot, an angled member having lateral extensions adapted to bear against the inner wall of the box, and a part extending through an aperture in said box, 90 said extended part having a threaded aperture, a headed screw fitted in said threaded aperture, and a slotted extension upon said cover engaged by said screw, as set forth.

95 In testimony whereof, I hereunto affix my signature in the presence of two witnesses.

LOUIE T. LA PAUGH.
